UNITED STATES PATENT OFFICE.

LITA SHINN AND BESSIE SHINN, OF MUSKOGEE, OKLAHOMA.

HAND-PAINTED RAG DOLL.

1,327,884.

Specification of Letters Patent. Patented Jan. 13, 1920.

Application filed May 31, 1916. Serial No. 100,995.

To all whom it may concern:

Be it known that we, LITA SHINN and BESSIE SHINN, citizens of the United States, residing at Muskogee, in the county of Muskogee and State of Oklahoma, have jointly invented a new and useful Improvement in Hand-Painted Rag Dolls, of which the following is a specification.

Our improvements relate to dolls, and more particularly to that class commonly known as rag dolls, and our object is to produce a doll that will stand the rough usages of play and at the same time conform more nearly to the human anatomy in construction, and singularly attractive and pleasing as a finished production.

We attain these objects by a series of patterns illustrated in the accompanying drawing, in which—

20 Fig. 1 is a front view of a pattern of the back part of the head of a rag doll; it is circular in form, approximately two and one-half inches in diameter, corresponding to a completed doll of about eighteen inches in height; the diameter will vary with heights, as will the dimensions of all the other parts herein predicated on a doll with the named height.

Fig. 2 is a front view of a pattern for the 30 middle section of the head; it is approximately thirteen inches in length and three inches in width; the upper corners of each end are cut away by a diagonal starting about one and one-half inches from the bottom and terminating at about the same distance from the removed corner on each line.

Fig. 3 is a front view of the pattern for the face being circular in form with an approximate diameter of four inches.

40 Fig. 4 is a front view of the pattern for one-half the neck of the doll, being about 12 inches long by about two inches in width.

Fig. 5 is a front view of the pattern for one-half of an arm, being nine inches in its 45 longest prolongation by about two and one-fourth inches at its widest part; the dotted lines are the shoulder and elbow joints, a decided improvement over existing forms. Attention is also called to the hand and its 50 fingers.

Fig. 6 is a front view of the pattern for one-half the front view of the body, and

Fig. 7 is a like view of one-half the back of the body. Where parts are given in halves 55 it is understood that the halves not shown

are exactly like those that are shown in outline and measurements. The half of the front view is about ten and one-half inches in its longest part by about three inches in width; the back view is about ten inches in 60 its longest way by about three inches in width. The dotted lines on the front view are for tucks one inch from the lower edge of the body, which make the lower front of the body section more natural, giving freer 65 movement and a more graceful and life-like appearance.

Fig. 8 is a side view of the pattern for one-half the leg, being nearly ten inches in its longer part and four inches in width. 70

Fig. 9 is a front view of the pattern for sole of one foot. It is understood that slight variations in all these measurements are admissible, none of which will mar the completed appearance of the doll; it is also understood that marked variations are permitted 75 where the object is to produce an abnormal creation.

Fig. 10 is a perspective view of the completed doll in a standing position, except 80 that each doll is hand painted to bring out the hair, the eyes, the nose, the mouth and cheeks in the most attractive and life-like manner.

Fig. 11 is a perspective view of the completed doll in a sitting position. 85

These patterns, together with the method of putting them together, and together with the hand painted finished features make the rag dolls conform more nearly to human 90 forms and constitute a new and valuable improvement in the art of making rag dolls.

Our patterns of all the sections of the doll are shown in the drawings. We obtain the completed head by stitching the back part of 95 the head, Fig. 1, to the middle part of the head, Fig. 2, on a double thread sewing machine, the face sides of the cloth inside. This is then stitched in the same manner to the face, Fig. 3. This partially completed 100 head is then reversed, so that the seams are inside, and filled with cotton. In the same manner the arms, the body, the legs and the feet are prepared. The head is then fastened to the body as follows: 105 It is sewed securely to the body by a whip stitch; then the neck piece, Fig. 4, is folded and bound tightly so as to form the neck and is secured on both edges by a whip stitch. This provides for a slight 110

movement of the head, forward and back and laterally and is an improvement in the jointure of the neck.

Before attaching the arms to the body 5 stitches are run along the dotted lines, Fig. 5, for the shoulder and elbow joints. These jointures are important as they provide flexibility and greater movement not alone for the whole arm but for the forearm, while 10 aiding in a more natural muscular appearance. The completed arms are then fastened to the body by a whip stitch at the shoulders.

The legs are then fastened to the body in 15 the same manner. Attention is called to the manner in which the toes are formed by stitching and to the hand painted finger and toe nails, features contributing the elements of beauty and naturalness to the doll.

20 The material of which the various sections are made is a superior grade of cotton fabric chemically treated which renders it both washable and waterproof, each one stuffed with cotton. Each face is an original one 25 and hand painted—giving a glazed finish to the eyes hair and mouth that are novel and attractive.

We claim:—

1. In a rag doll a head, having a flexible back portion, a face portion, and an intermediate portion connecting said back and said face portions, a body portion and independent neck portions stitched to and connecting said head and body portions. 30

2. In a rag doll the combination of a reinforcing neck piece, a head portion stitched to the upper edge of the neck piece and a body portion stitched to the lower edge of the neck piece. 35

3. In a rag doll a foot comprising a bag-like portion having longitudinally directed toe partitioning stitches and toe-nails painted thereon. 40

4. In a walking doll comprising a body, a tuck stitched horizontally across the lower 45 front portion of the body approximately one inch from the lower edge and legs sewed firmly to the tuck.

LITA SHINN,
BESSIE SHINN,
